UNITED STATES PATENT OFFICE.

CHARLES F. IKLÉ, OF NEW YORK, N. Y., ASSIGNOR TO IKLÉ FRERES & COMPANY, OF ST. GALLEN, SWITZERLAND.

DESIGN FOR EMBROIDERED TRIMMING.

48,900.

Specification for Design.

Patented Apr. 18, 1916.

Application filed February 19, 1916. Serial No. 79,465. Term of patent 3½ years.

To all whom it may concern:

Be it known that I, CHARLES F. IKLÉ, a citizen of the United States, residing at the borough of Manhattan, city, county, and State of New York, have invented a new, original, and ornamental Design for Embroidered Trimming, of which the following is a specification, reference being had to the accompanying drawing, forming a part thereof.

The figure is a plan view of a portion of the trimming, showing my new design.

Copies of this patent may be obtained for five cents each, by addressing the "Commissioner of Patents, Washington, D. C."

I claim:

The ornamental design for embroidered trimming, as shown.

In testimony whereof I have signed this specification in the presence of two subscribing witnesses.

CHARLES F. IKLÉ.

Witnesses:

JAMES M. COBHAM,
PAUL GROEBLE.
